CABINET FOR TREATING DISEASES BY LIGHT.

APPLICATION FILED JAN. 17, 1906.

2 SHEETS—SHEET 2.

UNITED STATES PATENT OFFICE.

BENJAMIN F. FULLER, OF EL RENO, OKLAHOMA TERRITORY.

CABINET FOR TREATING DISEASES BY LIGHT.

No. 828,738.

Specification of Letters Patent.

Patented Aug. 14, 1906.

Application filed January 17, 1906. Serial No. 296,511.

To all whom it may concern:

Be it known that I, BENJAMIN F. FULLER, a citizen of the United States, residing at El Reno, in the county of Canadian, Territory of Oklahoma, have invented a new and useful Cabinet for Treating Diseases by Light; and I do hereby declare the following to be a full, clear, and exact description of the invention, such as will enable others skilled in the art to 10 which it appertains to make and use the same.

This invention relates to certain new and useful improvements in cabinets for treating various diseases; and the object of the invention is to provide an octagon-shaped cabinet having a suitable base and a conical-shaped top which also conforms to the octagon-shaped cabinet, as shown clearly in the accompanying drawings. The various sides of 15 this cabinet are hinged together, as shown, and provided upon the inner faces thereof with mirrors, whereby when the cabinet is closed and in readiness to be used the inside will appear substantially as one mirror, only 20 that the mirrors upon the faces of the different sections of the cabinet will reflect at different angles. The top is also provided upon its under surface with mirrors and is provided with four or more arc-lamps, which in combination with the mirrors produce violet light. 25

Another object of this invention is to provide a device of this character which is portable and which also can be knocked down and packed for shipment in a small compass.

30 The invention comprises further objects and combinations of elements, which will be hereinafter more fully described, and shown in the accompanying drawings, and the novel features thereof will be particularly pointed out by the appended claims.

To obtain a full and correct understanding of the details of construction and combination of features, elements, and advantages, reference is to be had to the hereinafter-set-forth description, in connection with the accompanying drawings, wherein—

Figure 1 is a perspective view of the cabinet in readiness for use. Fig. 2 is a longitudinal vertical section through the cabinet. 45 Fig. 3 is a detail view of the faces forming the octagon-shaped cabinet, showing said faces hinged together in sequence. Fig. 4 is a detail view of the bottom, showing the hinged door to allow for the entrance of the patient to be treated; and Fig. 5 is a cross-sectional view on line 5 5 of Fig. 2. Fig. 6 is a detail

view of rod 24, showing the manner in which it is connected with the cabinet.

Making renewed reference to the accompanying drawings, wherein similar reference characters indicate the corresponding parts in the several illustrations by figures, 1 designates the base, which is octagon-shaped and provided with rectangular recesses 2, conforming to the shape of the bottom, as shown 65 in Fig. 4 of the accompanying drawings. Said bottom is also provided with legs 3 to allow the cabinet to stand the desired distance from the floor. Said recesses 2 are adapted to receive a rib 4, which projects and 70 is also integral with the end of each face of the octagon-shaped cabinet when said faces are placed in proper position, as shown clearly in Fig. 2 of the drawings. The faces forming the cabinet are hinged together in 75 sequence by hinges 5 in such a manner as to allow said faces to be folded in a small compass when said cabinet is disassembled.

Provided upon the inner face of each of the faces forming the cabinet are mirrors 6, 80 which mirrors are beveled, as shown at 7, so as to engage the inclined side walls 8 of a recess 9, which extends the full length of the faces forming the octagon. The top 10 comprises a number of faces 11, conforming to 85 the same number of faces of the octagon, said faces of the top converging to an apex, as shown. Said faces 11 are hinged together by hinges 12 in order to allow said top to be folded. The faces 11 of the top 10 are also 90 provided with mirrors 13, which are beveled in a similar manner to the mirrors 6 and adapted to engage the inclined side walls 14 of a recess 15, which recess 15 converges to an apex, as shown. The outer edges of the faces 95 of the top are provided with rabbets or a recess 16, so as to be firmly held from displacement upon the upper edges of the faces of the cabinet.

The top upon the inner side is provided with 100 a plurality of arc-lamps 17, which, in combination with the mirrors, reflect the light at different angles, produce a violet light which is designed to be used for treating various diseases. One of the faces forming the sides 105 of the cabinet is adapted to be used as a door 18 and is provided with a lock 19 in order to securely lock the cabinet after the patient has been placed in the same. Adjacent to the lower edge of the door 18 is an additional 110 door, or, in other words, a trap-door 20, formed by a section of the base of the cabinet,

which is hinged, as at 21. Said trap-door co-operates with the door 18 and is also provided with a lock 22 to securely hold the door 20 together and to allow the person to walk thereover.

From the foregoing it will be plainly observed that by the provision of a polygon-shaped cabinet having mirrors upon the inner faces of the top and the inner faces of the sides various diseases may be treated by a violet light, which is produced by the combination of arc-lamps and the angled reflections of the light from the mirrors and when manufactured in accordance with the accompanying drawings may be sold comparatively cheap.

To prevent the spreading at the top of the flat section, a suitable rod 24 is provided, which is pivoted, as at 25, and spanning the opening of the door 18. This rod is provided with a rectangular enlargement which is adapted to be seated within a recess 27 when it is desired to hold the upper part of the sections together. To securely hold the top and bottom against the upper and lower edges of the flat section, suitable tie-rods 28 are provided, which are pivoted, as at 29, in recesses of the base of the cabinet, as shown in the drawings. The upper parts of the rods 28

are adapted to engage recesses 30, formed upon the edge of the top, as shown, after which nuts 31 are used for clamping the top and bottom together against the upper and lower edges of the flat sections.

Having thus fully described the invention, what is claimed as new and useful by the protection of Letters Patent is—

1. A polygon-shaped cabinet for treating various diseases by light formed of flat sections hinged together in sequence, mirrors carried by said sections, and mirrors also carried by the inner face of the top in combination with arc-lamps.

2. A cabinet for treating diseases by light, comprising a casing, a top and bottom, mirrors having beveled sides, recesses formed upon the inner circumference of the casing, and having inclined walls to receive said mirrors in combination with suitable lamps, and vertically-disposed rods connecting said tops and bottoms together.

In testimony whereof I have hereto affixed my signature in the presence of two witnesses.

BENJAMIN F. FULLER.
